(No Model.)

E. PROUTY.
POWER TRANSMITTING DEVICE.

No. 443,608.

Patented Dec. 30, 1890.

UNITED STATES PATENT OFFICE.

ENOCH PROUTY, OF CHICAGO, ILLINOIS, ASSIGNOR OF ONE-HALF TO OLIVE S. PROUTY, OF SAME PLACE.

POWER-TRANSMITTING DEVICE.

SPECIFICATION forming part of Letters Patent No. 443,608, dated December 30, 1890.

Application filed September 22, 1890. Serial No. 365,717. (No model.)

To all whom it may concern:

Be it known that I, ENOCH PROUTY, a citizen of the United States, residing in Chicago, in the county of Cook and State of Illinois, 5 have invented a new and useful Improvement in Power-Transmitting Devices, of which the following is a specification.

This invention relates to devices for carrying power from a motor to the axle of street-cars; but while it has been specially devised with reference to this use, many features of the invention can be employed in actuating machinery of different kinds.

The object of the invention is to provide 15 means in these transmitting devices whereby the driven axle or shaft can be started gradually by power from a continuously-moving motor.

Another object has been to adapt these 20 transmitting devices to be geared to a continuously-moving motor in such manner that they will not transmit power except when it is desired that they should do so; also, to render them automatic in assuming the position 25 wherein they are neutral or non-active; also, to so construct them that they will not accidentally assume any operative position and start the car when that result is not desired.

The invention further consists in the novel 30 devices and novel combinations of parts and devices herein shown and described, and more particularly pointed out in the claims.

In the accompanying drawings, which form a part of this specification, Figure 1 is a longitudinal vertical section of a street-car embodying my invention. Fig. 2 is a side elevation of the power-transmitting devices detached. Fig. 3 is a front view of the part shown at Fig. 2. Figs. 4 and 5 are detail sections on the lines 40 44 and 55 of Fig. 3. Fig. 6 is a section upon the line 66 of Fig. 1. Fig. 7 is a side and Fig. 8 a front elevation of the clutch for actuating the axle.

In said drawings, A represents a car or vehicle, provided at its front end with a motor B, the driving-shaft of such motor carrying a wheel b.

C is a vibrating lever pivoted stationarily at its lower end upon a pivot c, supported in 50 a depending bracket D, attached to the car. The pivot c is caused to securely hold the lever

by reason of its enlarged end d, which is seated in the lever, as shown at Fig. 5. At its upper end said lever is joined to the motor-wheel b by a sliding connection consisting of a slide 55 E, embracing the lever and having a pivotal connection e with the motor-wheel.

It will be readily seen from the construction thus far described that the rotation of the motor-wheel will impart a vibrating motion to the upper end of the lever C, and as the motor is intended to be run continuously the lever C will also be continuously vibrated. Extending from the lower end of the lever, or rather from a sliding box F mounted thereon, is a pitman G, carrying motion to the car-axle or other shaft to be driven. This pitman is adapted to communicate a slow movement or a rapid one, or one which may gradually increase in speed by reason of the 70 changes in position of which it is capable relative to the center on which the lever C vibrates. It is pivotally attached to the sliding block by the pivot g, having an enlarged head f. The sliding block has a dovetail connection with the lever, and its position on said lever is changed at will by the driver or attendant by mechanism which will now be described.

Extending longitudinally of the car is a bar 80 H, supported in suitable bearings h and carrying at its end a rack i, meshing with a horizontal pinion J, mounted upon a hollow journal j. This shaft has an angular opening 85 through it, as shown at Fig. 6, and this opening is adapted to receive a key K, through which the driver may turn the pinion J and slide said bar H. The movement thus given to the bar H raises or lowers the sliding block F by means of the elbow-lever L, pivoted at 90 m to the bracket D and connected to bar H by a pin M, working in the slot n of one end of the elbow-lever, and a pitman N, joined to the outer end of the elbow-lever and also to the block. Movement of the bar H to the left 95 rocks the elbow-lever to the position indicated by broken lines at Fig. 2 and lifts the sliding block to the position also indicated at Fig. 2. In this elevated position, it will be at once observed, a considerable movement will 100 be imparted to the pitman G because of the distance from the center of the vibration of

the lever C to which the pivotal attachment of the pitman to the sliding block has been moved. Of course the block can be raised to this elevated position quickly or slowly, as desired, or it may be left at any intermediate position, so that the speed of the movement carried to the shaft is under complete control. It will also be noticed that the lever C may vibrate when the pivots *g* and *c* are together without actuating the pitman G at all; further, that when the block is in its lower operative position, while the stroke it imparts is shorter than in its upper position, yet it is possessed of more power than in the latter position, so that it is capable of giving to the axle what is desirable in all car-starters—viz., great power accompanied with slow motion. It will also be observed that should the attendant fail to move the bar H to its normal position when the car is to be stopped, and thereby bring the pivots *c* and *g* in register with each other, the weight of the sliding block F will cause it to move gradually down to its lowest position, and thus accomplish automatically a cessation of motion of the parts actuated through the transmitting devices. The gravity of the block also prevents any tendency to rise and bring about an operative condition, and thus renders some act of the attendant necessary in order to start the axle.

In conjunction with the variable transmitting devices above described, any appropriate clutch for communicating motion given to the pitman G to the car-axle (or other shaft) may be employed; but I prefer to use a clutch upon each of the car-axles and to gear the clutches together in such manner that each will be acting when the other is moving back for a fresh hold. I also prefer the construction of clutch particularly illustrated at Figs. 7 and 8.

I mount upon the axle O or other shaft a grooved wheel P, the groove being formed with sloping sides *p* and an inner vertical-sided portion *o*, and employ with such groove-wheel a pawl Q, which is preferably formed of a triangular piece of metal with its lower edge beveled off and a central slit *q* adapted to give a slight amount of spring to its edges which come in contact with the wheel. The pawl conforms to the groove of the wheel, as shown at Fig. 8, and when forced into contact therewith the slit in the pawl allows the sides of the latter to yield slightly and admit the pawl a greater distance within the groove, so as to permit a stronger hold than could be obtained were the pawl solid at this point.

The friction-wheel P is made in severable halves, so that it may be secured to the axle after the wheels have been put on. It is provided with a hub *p'* at either side, likewise made in halves and carrying ears *p''*, whereby the two halves of the wheel and hub may be bolted together. The wheel is keyed to the shaft, as shown at *p''*.

The pawl is made wide at its operating end in order to prevent its riding past the crown

of the wheel, and also to enable it to operate at either side of the wheel-crown and actuate the wheel in either direction, as desired. It is connected to the pitman G by the wrist-pin *r*, but is loose upon said pin, so that its position may be controlled by the spring S, which is joined at one end to the arm R and at the other end to an arm *s*, pivotally supported in an upward exterior *s'* of the pawl. Said arm R is supported from the hub of wheel P and serves in turn to support the wrist-pin. This support R may also be made in parts, so as to be bolted in position and removed at pleasure. It is loose upon the wheel-hub, and of course supports the wrist-pin without being rigid therewith. Stops *s''* are provided upon the exterior *s'* to limit the downward movement of the arm *s*. In the position shown at Fig. 7 the spring exerts a pull upon arm *s* and tends to throw the operating end of the pawl to the right, and the pawl in this position is adapted to engage the wheel upon the left side and cause the rotation of the latter in the direction indicated by the arrow. The reciprocations of the pitman G will now force the pawl into contact with the wheel at each of its movements in one direction, and in its movements in the opposite direction will carry the pawl back to enable it to take a fresh hold.

The spring S determines the inclination of the pawl and the side of the wheel which shall be engaged, and hence I make the arm *s* so that it may be reversed to the position shown in broken lines in Fig. 7, and thus cause the spring to pull in the opposite direction and incline the pawl to act upon the other side of the wheel. This reversal is brought about by means of a shifting-rod T, carrying trips *t* and actuated by the car-driver by means of the shaft K, which may be placed in the hollow of pinion *u* when the car is to be reversed. Pinion *u* meshes with the rack V upon said rod. One of the trips *t* encounters with each movement of the rod a pin *w*, carried by the crank W, mounted upon the shaft of arm *s* at each actuation of said shifting-rod and reverses the arm *s*.

The car is preferably provided with means for actuating the rods H and T at each end, so that the driver can stand on either platform and still retain control of the transmitting devices. Anti-friction rollers *y* may be used to keep the bar H up against the pinion J, as shown at Fig. 6.

In order to gain a forward impulse at the rear axle while the pawl at the front axle is moving back for a fresh hold, I provide the rear axle with a clutch, which may be similar to that already described, and connect said clutch by means of a pitman G' to a downward extension R' of the arm R upon the forward axle. As the arm R moves with the pitman G the extension R' will communicate similar reciprocations to pitman G, reverse, however, in direction. Consequently when the pawl of the forward clutch is actuating

- the forward axle, the rear wheel will be moving back preparatory to a new hold, and when the forward clutch is moving back, the rear clutch will be actuating its axle, and hence the forward impulse will be continuous, or nearly so, the actuations succeeding each other so rapidly as to render the power nearly continuous. This feature will also be found advantageous in starting the car, because there will be no perceptible interruptions in the transmission of power to the axles, one axle beginning to receive motive force as soon as the power has ceased at the other.
- 15 The trips *t* are preferably pivoted to rod *T*, as indicated, so that should they by any means pass beyond or get over the pin *w* they will ride freely on it, and when they have passed beyond it will fall to the position indicated. They are sustained in the latter position by the stops *t'*.
- The reversing of the car can only be accomplished by taking out the key *K* from sleeve *j* and inserting it in sleeve of pinion *u*, so that the driver is not likely to reverse his motive power through fright or absent-mindedness while the car is in motion.
- The operation of the invention will be fully apparent from what has been already written.
- 30 The key *K* carries a ratchet *z*, and a pawl *3* is provided to engage this ratchet. By this means when the key has been operated to raise the slide the parts may be locked in position to which they have been moved, thereby retaining the slide in any operative position desired. By releasing the pawl the slide will quickly return to its lowermost position by gravity and discontinue the motion at the axle.
- 35 I claim—
1. The combination, with the motor and the axle or shaft to be driven, of a vertical lever pivoted at its lower end and vibrated by the motor at its upper end, a slide movable vertically on said lever above its pivot and mechanically connected to the axle or shaft, and means for raising said slide when it is desired to start or increase the speed, the gravity of said slide tending to depress and retain it in its neutral position, substantially as specified.
- 40 2. The combination, with a car-axle, of the motor, the vibrating lever actuated by the motor, the slide upon the lever, the clutch upon the axle, the pitman connecting said slide and clutch, the slotted elbow-lever, the pitman joining said elbow-lever to the slide, and the longitudinal bar *H* for swinging said elbow-lever, substantially as specified.
3. The combination, with the vibrating lever and the slide mounted thereon, of the slotted and pivoted elbow-lever *L*, pitman *N*, bar *H*, and means for actuating said bar at will, substantially as specified.
4. The combination, with the motor, the vibrating lever, and the movable slide, of a pitman and clutch carrying power to the first axle, and a second pitman and clutch connecting the first axle with the second axle, substantially as specified.
- 70 5. The combination, with the motor, the vibrating lever, and the movable slide, of a pitman and clutch carrying power to the first axle, and a second pitman and clutch connecting the first axle with the second axle, said clutches alternating with each other in actuating their respective axles, substantially as specified.
6. The combination, with the motor, vibrating lever, and movable slide, of a pitman and clutch carrying power to the first axle, and a second pitman and clutch deriving power from the clutch of the first axle and communicating power to the second axle, substantially as specified.
- 80 7. In a car, the combination, with the axles, of the motor and power-transmitting devices having a clutch-connection to one axle, a pitman *G'*, receiving power from said clutch-connection, and a clutch actuated by said pitman at the other axle, substantially as specified.
- 85 8. The combination, with the axles, of a clutch mechanism at one axle, having a support *R* and extension *R'*, a pitman connected to said extension *R'*, and a clutch at the other axle actuated by said pitman, substantially as specified.
- 90 9. The combination, with the reversible pawl, of the arm *s*, pivoted to the pawl, the spring-connection *S*, the trips for reversing said arm, and a shifting-bar for moving the trips, substantially as specified.
- 100 10. The combination, in a clutch, with a friction-wheel having a groove with inclined sides *p*, of an inner vertical-sided portion *o*, and a pawl shaped to trip said inclined sides and having a vertical slit *q*, substantially as specified.
- 110 11. The combination, in a clutch, of a friction-wheel *P*, having a groove, with a wide pawl *Q* fitting said groove and adapted to act on the wheel in either direction at will, substantially as specified.

ENOCH PROUTY.
